UNITED STATES PATENT OFFICE.

ORRIN LELROY SMITH, OF CHICAGO, ILLINOIS.

DEVICE FOR HANGING PICTURES.

SPECIFICATION forming part of Letters Patent No. 579,333, dated March 23, 1897.

Application filed April 18, 1896. Serial No. 587,363. (No model.)

To all whom it may concern:

Be it known that I, ORRIN LELROY SMITH, residing at Chicago, in the county of Cook and State of Illinois, have invented a new 5 and Improved Device for Hanging Pictures or other Articles, of which the following is a specification.

This invention is an improved device for hanging and removing pictures or other articles, it being equally applicable to both operations.

The object of my invention is to provide a device which can be used in connection with the picture hangers or hooks now in common 15 use and one that can be used in connection with the ordinary wire or cord in general use before the adoption of the picture hook or hanger.

Formerly a nail was driven into the wall 20 and the wire or cord hung upon said nail; but at the present time the more common practice is to secure a picture-rod to the wall near the ceiling and support the picture hooks or hangers thereon. The great difficulty, however, occurs in placing the picture 25 hooks or hangers upon the rod, necessitating the use of a step-ladder, and, furthermore, in case it is desired to move the picture to one side or the other it is necessary to remove 30 the entire hook and picture to the adjacent place. All of these operations require a great deal of time and labor and are more or less tedious.

The object of my invention is to provide a 35 device which can be operated by either man, woman, or child, and by means of which the picture-hook carrying the wire can be properly placed upon the rod while the person stands upon the floor; and another object is 40 to provide a tool or device by means of which the picture, together with the wire and hook, can readily be removed from the picture-rod in case it is desired to take down the picture or move it to another place.

Another object is to provide a device for 45 the purposes described which will securely hold or lock the hook and wire therein while the same are being moved up or down to hang or take down a picture.

Another object is to provide a device for 50 the purposes intended which will securely engage or operate upon picture hooks or

hangers of all descriptions; and another object is to provide a tool of this kind in which the locking operation will be thoroughly 55 automatic.

With these various objects in view my invention consists in the peculiar construction of the various parts and in their novel combination or arrangement, all of which will be 60 fully described hereinafter, and pointed out in the claims.

In the drawings forming a part of this specification, Figure 1 is a view showing the invention in use, the wire and picture hook or 65 hanger held therein. Fig. 1^a is a view showing the picture hung, the wire and hook being apart from the hanger. Fig. 2 is a detail perspective view showing the device closed upon a picture hook or hanger. Fig. 3 is a 70 detail view showing the device open. Fig. 4 is a similar view from the opposite side.

In carrying out my invention I employ a pole A, of any desirable length, and upon the upper end thereof is mounted the thimble or 75 ferrule B, and extending upwardly from said ferrule is a flat arm C, bifurcated at its outer end, providing the members C' and C².

A fastening member D is pivotally mounted upon the upper end of the member C' by 80 means of a pivot D', said fastening member being essentially U-shaped, but the interior curve of the lower member is made somewhat greater, as shown at D², than the curve D³ upon the upper member.

Upon the exterior of the member D is produced a lug E, which curves gradually to a point, said lug being adapted to engage a leaf-spring F, fastened at its lower end to the arm C and bearing at its free end against the 90 exterior of the fastening member D, and as said member is moved up or down upon its pivot it is clear that the spring F will rest upon either the upper or lower side of the lug E and thereby hold the fastening member in 95 either a closed or open position.

The fastening member, being pivoted upon one member of the arm, swings toward the opposite member C² and engages the same in both its upward and downward movements, 100 the lower end of the member engaging a shoulder G, formed upon the end of the member C², while the upper end of the member D is formed with a shoulder G' to increase its

thickness and provide a firm bearing upon the shoulder G on the top of the member C². The shoulder G limits the upward movement of the fastening member as it is thrown open, 5 and said shoulder also limits the downward movement of said member as it is closed. The interior curve D³ of the member D is such that when the fastener is thrown down upon the member C² said edge D² will rest 10 slightly above the arm C and thereby form a suitable guide for the lower end of the picture hook or hanger H.

Now in operation in case it is desired to hang a picture upon the picture-rod I by 15 means of the hook H the picture-wire K is first inserted in the smaller or lower end of the picture-hook. The fastening member D is then thrown open and the lower member of the hook carrying the wire is inserted into 20 the said member. The weight of the picture bearing upon the hook immediately throws the lower portion of said member down and brings the upper member tight against the central portion of the picture-hook and binds 25 the same close against the member C² and its shoulder G, and the spring F prevents any possible dislocation of the parts. All of the parts being thus arranged, the picture with its wire and hook are elevated by means 30 of the pole and the larger end of the hook placed upon the picture-rod I. The hook thus sustains the weight of the picture and the pole with its attachment can be drawn downward, and in doing so the fastening member is thrown open, as most clearly shown, 35 thereby leaving the hook upon the rod and the wire secured in the lower end of the hook. As the fastening member is thrown open the lug E passes below the head of the leaf-spring 40 F and thereby holds said member open ready for the next operation.

In case it is desired to take the picture down or remove it to another place on the same rod the pole is raised, bringing the end of the 45 member C² under the lower end of the picture-rod, it being understood that the fastening member at this time is open. As the pole with its attachment is moved upward the weight of the picture upon the hook and the 50 upward pressure upon the pole cause the spring F to be overcome and the fastening member thrown down or closed, thereby securely holding the hook therein, and by continuing the upward movement of the pole the 55 hook can be removed from the rod and moved to another place, if desired, or taken down.

As before stated, my improved device can be used for hanging pictures upon the ordinary picture-nail in common use before picture hooks and rods, and in such case the wire is inserted in the fastener and then placed over the nail. The picture being thus supported, the pole can be drawn down, and in so doing the fastener will of course be opened. 60

Should it be desired to remove the wire from the ordinary nail, the fastener is first

thrown open and then projected up under the wire, and as soon as the wire comes in contact with the lower leg of the fastening member said fastening member is thrown 70 closed, and all possibility of the wire escaping therethrough will be avoided.

It will thus be seen that I provide an exceedingly cheap, simple, and effective device for hanging or removing pictures either in 75 connection with the picture hook or hanger or without said hook, and it will also be noted that the fastening operations of said device are thoroughly automatic.

Having thus described my invention, what 80 I claim as new, and desire to secure by Letters Patent, is—

1. An improved device for hanging and removing pictures or other articles, comprising a bifurcated arm having a shoulder at the 85 end of one member, a U-shaped fastening device pivoted at the end of the opposing member, said fastening device being adapted to contact with the said shoulder in both an open and closed position, substantially as shown 90 and described.

2. An improved device for hanging and removing pictures or other articles, comprising a bifurcated arm having a shoulder at the end of one member, a U-shaped fastening 95 member pivoted to the end of the opposite member, said fastening member having a lug upon the exterior, and a leaf-spring adapted to engage said lug and hold the fastener either open or closed, substantially as shown and 100 described.

3. An improved device for hanging pictures or other articles, comprising the bifurcated arm having a shoulder at the end of one member, the U-shaped fastening device pivoted 105 at the end of the opposite member, the upper leg of said fastening device having a shoulder, said fastening device having also a lug adjacent to the pivot, and the leaf-spring 110 adapted to engage said lug and hold the fastening device either open or closed, substantially as shown and described.

4. An improved device for hanging and removing pictures or other articles comprising the pole and thimble or ferrule, the arm projecting from said ferrule, and bifurcated at its upper end, the U-shaped fastening member pivoted near the upper end of one of the members, and having a lug intermediate its ends, and a lateral shoulder upon its upper 120 end, the upper end of the other member of the bifurcated arm having a lateral shoulder adapted to engage the lower end of the U fastening member and limit its upward movement, and the leaf-spring attached to the arm, 125 and adapted to engage the lug on the fastening member to hold the same open or closed, substantially as shown and described.
